(57) **CLAIM**

The ornamental design for a vertical holder, as shown and described.

DESCRIPTION

FIG. 1 is a perspective view of our vertical holder;
FIG. 2 is front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

The dashed lines represent environmental structure and form no part of the claimed design. All other surface(s) or portion(s) of our invention not shown in the figures or otherwise described in the specification, such as the inside bottoms of the pots, form no part of the claimed design.
